(57) **CLAIM**

The ornamental design for a valve assembly, as shown and described.

DESCRIPTION

FIG. 1 is a top front perspective view of a valve assembly showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The dot-dash lines in the Figures show an unclaimed boundary that forms no part of the claimed design.

It is certified that error appears in the above-identified patent and that said Letters Patent is hereby corrected as shown below:

Title Page

In the Description section, replace:

“FIG. 7 is a bottom view thereof.
The dot-dash lines in the Figures show an unclaimed boundary that forms no part of the claimed
design.”

with:

--FIG. 7 is a bottom view thereof.
The broken lines in the Figures show portions of the valve assembly that form no part of the claimed
design.
The dot-dash lines in the Figures show an unclaimed boundary that forms no part of the claimed
design.--
